UNITED STATES PATENT OFFICE.

CLARENCE SHAFFER, OF CLEARFIELD, PENNSYLVANIA.

SPIKE.

SPECIFICATION forming part of Letters Patent No. 791,373, dated May 30, 1905.

Application filed February 7, 1905. Serial No. 244,565.

To all whom it may concern:

Be it known that I, CLARENCE SHAFFER, a citizen of the United States, residing at Clearfield, in the county of Clearfield, State of Pennsylvania, have invented certain new and useful Improvements in Spikes; and I do hereby declare the following to be a full, clear, and exact description of the invention, such as will enable others skilled in the art to which it appertains to make and use the same.

This invention relates to spikes in general, and more particularly to the class of railway-spikes such as are employed for holding railway-rails to the ties, the object of the invention being to provide a spike having locking-bars which are adjustable into and out of position to engage in the tie and prevent withdrawal of the spike.

A further object of the invention is to provide such an arrangement as will permit of withdrawal of the barb into the body of the spike when it is desired to remove the spike.

In the drawings forming a portion of this specification, and in which like numerals of reference indicate similar parts in the several views, Figure 1 is a side elevation showing a spike embodying the present invention. Fig. 2 is a section taken longitudinally through the spike with the barbs projected, parts being shown in elevation. Fig. 3 is an elevation of one of the barbs. Fig. 4 is a top plan view of the nut.

Referring now to the drawings, there is shown a spike including a body 5, having at its upper end the usual head 6, the lower end of the body being pointed, as shown as 7, so that it may be driven into the tie. In the lower portion of the body 5 is a chamber 8, from the upper end of which there lead passages 9 and 10 upwardly through the sides of the body 5, and midway between these passages is a central passage 11, that extends from the chamber 8 upwardly and through the head of the spike. In the passage 11 is disposed a screw which rotates loosely in the passage and the lower threaded portion of which enters the chamber 8. The screw is illustrated at 12 and comprises a head 13, which enters the countersink 14 at the upper end of the passage 11. The head of the

screw is slotted for engagement of a tool for rotating the screw. The lower end of the screw 12 is engaged in a rectangular nut 15, which is slidable vertically in the chamber 8, which latter is rectangular in cross-section to hold the nut against rotation. Thus as the screw is rotated in one direction or the other the nut is moved vertically in the chamber. 55

At opposite sides of the nut 15 are notches 16, which receive the reduced necks 17 at the lower ends of barbs or fingers 18, which are tapered upwardly. The barbs or fingers are of such dimensions that they may lie entirely within the body of the spike, with their upper 60 or pointed ends against the upper walls of the corresponding passages 9 and 10. When the nut 15 is moved upwardly, the barbs or fingers are raised, so that their upper ends project from the body of the spike and by engagement in the tie serve to prevent withdrawal 65 of the spike. When it is desired to withdraw the spike, the nut is fed downwardly by correspondingly rotating the screw, as will be understood. The heads at the lower 70 ends of the barbs, which result from reducing the barbs in the formation of the necks 17, prevent upward disengagement of the barbs from the nut, while the bodies of the barbs themselves prevent downward disengagement. 75

What is claimed is—

A spike comprising a body and a head, said body having a chamber in its lower portion, a central longitudinal passage leading 80 from the chamber through the head of the spike and side passages leading from the chamber and upwardly and outwardly through the sides of the spike, barbs disposed with their lower portions in the chamber and having their upper ends sharpened and disposed in the side passages, a nut in the chamber with which the barbs are connected, and a feed-screw passed through the central passage into the chamber and engaged with the nut. 90

In testimony whereof I affix my signature in presence of two witnesses.

CLARENCE SHAFFER.
